UNITED STATES PATENT OFFICE.

FRANK L. MICHAELS AND GEORGE WELLING, OF COVINGTON, KENTUCKY.

WINDOW-SCREEN.

974,689.

Specification of Letters Patent.

Patented Nov. 1, 1910.

Application filed October 4, 1909. Serial No. 520,788.

To all whom it may concern:

Be it known that we, FRANK L. MICHAELS and GEORGE WELLING, citizens of the United States, residing at Covington, in the county of Kenton and State of Kentucky, have invented certain new and useful Improvements in Window-Screens, of which the following is a specification.

Our invention relates to a window screen, primarily of that class in which two frames are provided in slidable connection with each other, whereby the screen as a whole can be adjusted to varying widths of window frames.

15 The object of our invention is to provide a window screen formed of two duplicate sections, with means for slidably securing the sections together to form an adjustable screen.

20 Another object of our invention is to provide a screen frame, formed of sheet metal, in which the sides are all of the same formation, together with the particular means for securing the side strips at their meeting 25 edges.

The features of the invention are more fully set forth in the description of the accompanying drawings, forming a part of this specification, in which:

30 Figure 1 is a front view thereof. Fig. 2 is an enlarged detailed view of one of the corners. Fig. 3 is a section on line *a*, *a*, Fig. 1, of one of the frame sections. Fig. 4 is a section on line *c*, *c*, Fig. 2. Fig. 5 is a section on line *x*, *x*, Fig. 1. Fig. 6 is a section on line *w*, *w*, Fig. 1. Fig. 7 is a section on line *b*, Fig. 1. Figs. 8 and 9 are cross sections, through the frame strip, showing a modified form of attaching the strips.

40 The screen comprises two frame sections 1, 2, of duplicate construction, with intermediate top and bottom connecting plates 3, preferably secured to each of the sections, and of such formation as to permit the opposing strips to be intermeshed and slid thereon. By making all the frames of a given formation, the material can be turned out in strips and made up into sections requiring but single sets of dies, in which no 45 right and left formations are required. This is a material saving in the cost of the manufacture and assemblage in the manufacture of stock formed screens. As both 50 frame sections are duplicates, it will only

be necessary to describe the construction of 55 one of the sections.

The frame is preferably constructed of sheet metal formed in strips primarily as shown in cross section, Fig. 6, in which:—1^a represents the body portion of the strip, 60 formed with a medial rib or bead 2^a to strengthen the same. 4 represents a right angled bend, adapted to form a hook when turned parallel with the body portion 1^a, between which the wire cloth 5 is secured. 65 The opposite edge of the strip 1^a is provided with the hooked bend 6, opposite the hook bend 4. The edges of the strip are preferably bent to form an edge bead 7, to provide a rounded edge, especially desirable 70 upon the edge over which the wire cloth passes, preventing the edges from injuring the cloth, or forming an obstruction which would follow were the edges left sharp. The strips are preferably formed with the 75 hooked ends 4, turned to a right angled flange and folded down upon the wire cloth, after the strip has been formed into a frame.

The corners of each screen frame are preferably made, as illustrated in Figs. 2, 4, by 80 cutting each strip to a miter edge and providing a lock plate 8, for securing the two ends of the strips to form a frame. The lock plate 8 is preferably made from a sheet of metal of right-angle form, overlapping 85 the meeting corner ends of the frame strips, with its marginal right-angled edges engaged between the body portion 1^a and hook bends 4 and 6, of each of said frame strips. 9 represents a slot formed in the lock-plate 90 with the metal in rear thereof slightly arched so as to bring the same above the plane of the remainder portion of the metal plate, and through which slot the meeting corner edges of the hook bends 4 of each 95 strip, project, as illustrated in Fig. 4. Thus a portion of the plate occupies a position below the hook bends with its intermediate portion above the hook bends 4 of both meeting ends of the frame strips. This 100 forms a very secure corner lock and can be additionally secured by riveting the corner plate 8 to each strip.

Each frame section is provided with three of its sides formed from a strip of metal, as 105 described, forming the outside edges of the frame, with the fourth side or edge provided with a tie-strip 10, connecting the

2
ends of two of the frame strips, for forming a frame section. This strip is preferably connected to the top and bottom strips of the frame section, as illustrated in Fig. 7, and is U-shaped in cross section, with the limbs bent upon themselves and between which the wire cloth is secured, and may be provided along one side thereof with a rib 11, adapted to engage the adjacent wire-cloth of the second section, so as to close the overlapping ends of the wire-cloth. The tie-strip 10 is slit at its ends, and one of the limbs thereof provided with a hook bend 14, engaging with the hook bend 4, the opposite limb 14^a extended to engage between the hook bend 6. The two sections are slidably united with the tie-strips intermediate, as follows: 13 represents a connecting plate, see Fig. 3, adapted to lie and be secured between the hook formations 4 and 6 of the frame strips, and provided along one edge with a U-shaped bend 12, with one limb projected exteriorly and parallel with the hook formation 6, of the strip 25 to which it is secured, adapted to form a slideway to receive a limb of the hook 6, of the frame strip of the second section, forming a slideable connection between the two frame sections, for adjusting the width of 30 the screen to any size of window. These slide-plates are all of duplicate construction and secured to the respective frame strips, one in rear of each end of each tie strip, to receive the hook bend 6 of the opposing 35 frame strip.

In the modification shown in Figs. 8 and 9, one of the limbs of the U-shaped tie-strip 10 is not provided with the end hook bends engaging over the hooks 4 of the frame 40 strips, but is cut away, while its opposite limb is extended and connected to a respective frame strip by means of a rivet.

Having described our invention, we claim:—

1. A window screen frame formed of sheet metal, and comprising strips each having a body portion with hook bends on each edge thereof, the meeting ends of said strips being cut on a miter, a connecting corner plate engaged between both hook bends of each strip, a notch being formed into said connecting plate through which the meeting edges of the inner hook bends project. 45

2. A window screen, comprising two slidably connected frame sections, each section composed of strips of sheet metal each having a body portion and hook bends on each edge thereof, said strips forming three sides of the frame, a tie-strip formed of sheet metal, U-shaped in cross section, with its ends slotted forming two separated limbs, the one provided with a hook bend adapted to engage with one of the hook bends of the frame strip, the opposite limb engaging the opposite strip hook bend. 55

3. A window screen, comprising two slidably connected frame sections, each section composed of strips of sheet metal, each having a body portion and hook bends formed on each edge thereof, one of said hook bends 70 adapted to form clasping means for the wire cloth, and a plate fixed to two sides of each frame section, provided with a bend forming a slide-way engaging with the relative opposed hook bend of the second frame 75 section. 60

In testimony whereof, we have hereunto set our hands.

FRANK L. MICHAELS.
GEORGE WELLING.
